UNITED STATES PATENT OFFICE.

NEAL TRIMBLE MCKEE, OF BRONXVILLE, NEW YORK, ASSIGNOR TO THE SUPER-HEATER COMPANY, OF NEW YORK, N. Y.

FEED-WATER HEATER ARRANGEMENT.

Application filed September 30, 1925. Serial No. 59,505.

The invention relates to the type of feed water heaters in which the water is heated by exhaust steam, and it has for its purpose the provision of an arrangement by which 5 the operation of such devices is improved particularly at times when there is no exhaust steam available.

My invention is illustrated in the accompanying two sheets of drawings in which 10 Fig. 1 shows a locomotive equipped with an exhaust steam feed water heater with my improvement applied to it; Fig. 2 shows on an enlarged scale a longitudinal section of an element in the arrangement; and Fig. 3 15 shows a modification of the element shown in Fig. 2.

The general disposition of the exhaust steam feed water heater and the related parts is not modified when my invention is used, but may be of the ordinary or any preferred type. The illustrated form shown in Fig. 1 may be briefly described as follows:

The body of the locomotive is designated by the numeral 1. The exhaust-steam feed- 25 water heater 2 is shown in an elevated position at the upper front end of the smokebox. This heater shown by way of illustration is of a well-known form and as its precise construction is immaterial as far as my 30 invention is concerned, it will be unnecessary to illustrate or describe it in detail. It is of the type known as surface heaters in which the water to be heated and the steam heating it do not mingle. But it will be 35 readily seen that this invention is equally applicable to heaters in which such mingling does occur.

Exhaust steam is carried from the base of the exhaust nozzle by means of pipe 3 to the 40 heater. The resulting condensate is carried off by means of pipe 4 and returns to the feed line 5 by means of connection 5^a. Water to be heated in the heater reaches pump 6 by means of pipe 5 and is delivered by it 45 through pipe 7 to the feed water heater. It leaves the feed heater and is fed to the locomotive boiler through pipe 8 and boiler check 9. The pump 6 receives steam to operate it through pipe 10 from the steam 50 turret 11. The exhaust from the pump is also carried to the feed water heater through pipe 12.

There are other steam driven auxiliaries 55 on a locomotive which are in practically constant operation, and the exhaust from which

is also carried to the feedwater heater. As representative of this class there is shown in the drawing the air pump 30. Steam for driving it reaches it through pipe 31, and the exhaust steam leaves by pipe 32, 60 which delivers it to pipe 12, to join any exhaust issuing from the water pump.

The arrangement so far described is not novel. One difficulty experienced with it is that when the locomotive throttle is shut off, 65 and there is therefore no exhaust steam which could reach the heater through pipe 3, the water forced by the pump through the heater will not receive any heat in the heater but will pass on to the boiler in a cold state. 70 This is objectionable as is well understood by boiler men.

I am aware that means have been suggested in the past for obviating this difficulty. In fact, my own United States application #37,462, dated June 16, 1925 proposes one way of remedying it. The present invention has the same purpose in view, but does it by other means.

I carry the live steam operating the pump 80 from pipe 10 through an automatic valve 13. This automatic valve has a connecting pipe 14 leading from it to the steam pipe 15 which steam pipe delivers steam to the main engine. The details of valve 13 are more 85 clearly illustrated in Fig. 2. Pipe 10 connects to the valve at 16, and steam passing from the valve to the pump leaves at 17. The passage 18 from 16 to 17 is controlled by means of a valve 19. This valve has a 90 cylindrical stem 20 reciprocating in a cylindrical bore in partition 21. There is a small hole 22 in the valve by which a small quantity of steam can pass from inlet 16 to outlet 17 when the valve is in its closed position, 95 as in the figure.

Alined with the cylindrical bore in partition 21 is the larger cylindrical bore 23 in which reciprocates piston 24. This piston abuts against the end of stem 20. Pipe 14 100 is arranged to communicate with the left end as viewed in the figure of the bore 23.

A drain pipe 25 is screwed into the opening 26 at the right end of bore 23. This is to allow any steam to escape which may leak past piston 24.

When the engineer opens the main throttle and there is steam pressure in pipe 15, a similar pressure will also exist at the left side of piston 24. The area of this piston 110

being larger than the area of valve 19, the piston will move towards the right and open valve 19. This position will be maintained as long as steam pressure above a certain point, exists in pipe 15.

When the throttle is closed, the pressure in 15 drops rapidly below the pressure required to hold the piston 24 in its position to the right and the live steam passing 10 through pipe 10 and from 16 to 17 will carry valve 19 toward the left and will seat it.

It will now be apparent that as long as there is steam in 15, or in other words as 15 long as there is exhaust steam to heat the feed water, valve 19 will be open and the pump 6 will operate at full capacity. When the throttle is closed and the pressure in 15 falls, or in other words when there is no 20 exhaust steam to heat the feed water, valve 19 will close. The leakage through 22, however, is sufficient to keep the pump moving slowly. This is a very important feature of 25 my proposed arrangement. If the pump is allowed to stop completely, there will always be danger of its becoming airbound and in any case when it resumes its action, it will do so very suddenly, such sudden 30 start being accompanied by objectionable shocks. I make the opening 22 of such size that the pump will keep moving, but will not force into the boiler water in objectionable quantities.

The small amount actually delivered is 35 as a matter of fact heated sufficiently by exhaust steam from one or another of the constantly operating auxiliaries exhausting into the heater, as a representative of which the air pump has been mentioned above. 40 One or more of these auxiliaries are almost certain to be furnishing exhaust steam at such times.

On the opening of the throttle by the engineer and the resultant opening of valve 45 19, the increase in speed of the pump stroke to full capacity is smooth and unaccompanied by any shocks or jars.

In Fig. 3 is shown a variation of the valve of Fig. 2, the variation consisting in 50 the fact that this valve can be positively opened by manual means when desired, being otherwise automatically operated just as the one of Fig. 2.

The valve 19 here has a projecting stem 55 40 with an enlarged head 41. A yoke 42 engages this head in such a manner as to leave enough play for the automatic operation of the valve during normal periods. The yoke is carried by a stem 43 which is 60 in threaded engagement with the cover 44 and which extends through the cover and has means 45 on its outer end for manual operation. In the position illustrated the yoke permits the automatic operation. A 65 stop 46 prevents the yoke from being

screwed in too far and preventing the automatic function. The object of this arrangement is to make it possible to open valve 19 manually at times when there is no steam in the steam pipe 15, and when it may for 70 some reason become desirable to work the pump. This is accomplished by screwing out stem 43 until the yoke 42 engages the head 41 and moves valve 19 off its seat.

What I claim is:

1. In a locomotive the combination of an exhaust steam, feed-heater, a pipe supplying exhaust steam from the main engine to it, a pipe supplying feedwater to it, a pipe carrying feedwater from it to the boiler, a pump supplying water to said second named pipe, a pipe supplying steam to the pump, a steam pipe supplying live steam to the main engine, and a valve in the pump steam pipe responsive to pressure conditions in 85 the main engine steam pipe to open when the pressure is above a certain point and to close when it is below such point.

2. In a locomotive the combination of an exhaust steam, feed-heater, a pipe supplying exhaust steam from the main engine to it, a pipe supplying feedwater to it, a pipe carrying feedwater from it to the boiler, a pump supplying water to said second named pipe, a pipe supplying steam to the pump, 95 a steam pipe supplying live steam to the main engine, and a valve in the pump steam pipe responsive to pressure conditions in the main engine steam pipe to open when the pressure is above a certain point and to close when it is below such point, there being provided a small leakage from one side of the valve to the other when seated, whereby the pump is kept moving slowly when the valve is closed.

3. In a locomotive the combination of an exhaust steam, feed-heater, a pipe supplying exhaust steam from the main engine to it, a pipe supplying feed-water to it, a pipe carrying feedwater from it to the boiler, a pump supplying water to said second named pipe, a pipe supplying steam to the pump, a steam pipe supplying live steam to the main engine, a valve in the pump steam pipe responsive to the pressure conditions in the main engine steam pipe to open when the pressure is above a certain point and to close when it is below such point, and hand operated means to open and close said valve irrespective of the pressure conditions in the main engine steam pipe.

4. In a locomotive, the combination of an exhaust steam feed-heater, a pipe supplying exhaust steam from the main engine to it, a pipe supplying feedwater to it, a pipe carrying feedwater from it to the boiler, a pump supplying water to said second named pipe, a pipe supplying steam to the 125 pump, a steam pipe supplying live steam 130

to the main engine, a steam driven auxiliary in substantially constant operation, a pipe carrying the exhaust from said auxiliary to the heater, and a valve in the pump steam pipe responsive to the pressure conditions in the main engine steam pipe to open when the pressure is above a certain point and to

close when it is below such point, there being provided a small leakage from one side of the valve to the other when seated, ¹⁰ whereby the pump is kept moving slowly when the valve is closed.

NEAL TRIMBLE McKEE.
